CLAIM

The ornamental design for an operator cab on trailer, as shown and described.

DESCRIPTION

FIG. 1 is a top right perspective view of an operator cab on trailer showing our new design;

FIG. 2 is a front perspective view thereof;

FIG. 3 is a front view thereof;

FIG. 4 is a back view thereof;

FIG. 5 is a side view thereof;

FIG. 6 is a side view thereof showing the side opposite that shown in FIG. 5;

FIG. 7 is a top view thereof; and,

FIG. 8 is a rear perspective view thereof.

The broken lines are for the purposes of illustrating portions of the operator cab on trailer that form no part of the claim.
